US0D1109336S

(12) **United States Design Patent** (10) Patent No.: **US D1,109,336 S**
(45) Date of Patent: ** Jan. 13, 2026

(54) **SURGICAL BANDAGE**

(71) Applicant: **Connexicon Medical Limited**, Dublin (IE)

(72) Inventors: **Éadaoin Ledwidge**, Killiney (IE); **Niall McHugh**, Blessington (IE)

(73) Assignee: **Connexicon Medical Limited**, Dublin (IE)

(**) Term: **15 Years**

(21) Appl. No.: **29/877,597**

(22) Filed: **Jun. 8, 2023**

(30) **Foreign Application Priority Data**

Dec. 9, 2022 (EM) 015005791-0001

(51) **LOC (15) Cl.** **24-02**

(52) **U.S. Cl.**

USPC **D24/189**

(58) **Field of Classification Search**

USPC D24/158, 172, 187, 188, 189, 190, 191, D24/192, 199, 200, 206

(57) **CLAIM**

The ornamental design for a surgical bandage, as shown and described.

DESCRIPTION

The sole FIGURE is a top elevational view of a surgical bandage, showing our new design.

In the drawings, the broken lines depict elements of the surgical bandage that form no part of the claimed design.

1 Claim, 1 Drawing Sheet
